UNITED STATES PATENT OFFICE

1,935,778

DUST SEPARATOR FOR RAILWAY CARS

Charles Gilbert Hawley, Chicago, Ill., assignor
to Centrifix Corporation, Cleveland, Ohio, a
corporation of Ohio

Application July 28, 1930. Serial No. 471,333

6 Claims. (Cl. 183—90)

Railway cars and like moving vehicles that travel at high speeds present peculiar difficulties in the matter of maintaining proper and comfortable conditions within them. Purity of the contained air is required and the whole volume being small, its vitiation can only be avoided by constant supplies of fresh air, yet the air cannot be directly admitted from the atmosphere lest dust, rain or snow also enter. For this reason ordinary funnels set normally against the movement of the train have been replaced by more complicated devices intended to admit the requisite air and yet prevent the entrance of dust and moisture. Thus far no device of that character has been satisfactorily successful; and, the tendency is to revert to the older type funnels but to place them in reverse relation to the wind so that they shall operate as suction devices. The effect thereof is to lessen the air pressure within the car as contrasted with the external atmosphere, and this lessened pressure is relied upon to draw in the needed fresh air through such doors, windows and cracks as may be open. The system is negative in character, and as it is not an adequate excluder of dust it is favored quite solely upon the ground that the reversely positioned funnel tends to prevent the entrance of smoke from the tops of tunnels through which the train may pass. The present invention is adapted for utilization in the same way and will be so described; but its positive functions are of greater interest and more constant value.

This invention may be regarded as a reversion to the normal or old type funnel as a collector or receiver of air and by the use whereof in opposition to the velocity pressure of the wind, the car may be filled with air at a pressure that exceeds the static pressure of the external atmosphere. A state of higher pressure being produced within the car, it is clear that air will escape through any cracks or openings therein, and dust, instead of being drawn inward may actually be expelled from the car. If undefended, the normal funnel needed to secure this result, would admit impurities, as well as the air required, and this invention has for its further object, and comprises, means for conditioning the air by dynamically removing the foreign substances from the air that is to pass through the funnel and into the car.

This last is based upon the conception that an amplitude of air is available in the wind blowing toward the funnel, and that the wind approaches the funnel with energy which is ample for the cleaning of the air. Next, the invention is based

upon the use of that energy and the use or wastage of a portion of the air received, for the double purpose of centrifugally cleaning or conditioning the air and discharging the separated matters from the neighborhood of the funnel while an ample remainder of clarified pressure air enters the funnel.

Still further objects of the invention comprise the provision of a combined air intake funnel and antecedent air conditioner, in a unit form adapted to be variously positioned and used upon the exterior of a car; further, to provide a unit of large air conducting capacity and yet one of small size, compact organization, ample strength, durability and safety, and the initial and maintenance cost of which shall be small; and, to provide a unit structure which shall ornament the car instead of detracting from the appearance thereof.

Both the foregoing general description and the details of the fixture or apparatus, in its preferred form, will be clearly understood upon reference to the drawings that form part of this specification.

In said drawings, Fig. 1 is a sectional perspective view of the roof portion of a railway car bearing two air conditioning and exchanging fixtures, each embodying that form of this invention which best adapts it to be positioned upon the side of the car. Fig. 2 is a horizontal section of the car roof and of the two air conditioning fixtures, taken from Fig. 1;—Fig. 2a is a face view of the base plate of the fixture;—Fig. 3 is an enlarged horizontal section of one of the fixtures;—Fig. 4 depicts the bottom thereof, as viewed from beneath;—Fig. 5 is a longitudinal and vertical section, substantially on the line 5—5 of Fig. 3;—Fig. 6 is a transverse section on the line 6—6 of Fig. 3;—Fig. 7 is a similar section on the line 7—7 of Fig. 3;—Fig. 8 is an elevation of the air-receiving end of the fixture as viewed from the line 8—8 of Fig. 3 in the direction of the arrows;—Fig. 9 is an elevation of the opposite end thereof; and Fig. 10 is a view of the disc member.

The air conditioning fixture of this invention is composed wholly of metal, rust proof sheet metal being preferred for the purpose. It comprises two main elements, plus an associated or auxiliary element to which the main parts are fixedly secured. The first of the main elements comprises the before-mentioned air funnel, marked 14, and paralleling the side of the car; the other main element comprises the air conditioner proper, marked 8. The auxiliary element comprises the roof plate, marked 6. The latter is the base or anchorage by which the main ele-

ments 14 and 8 are fixedly attached to the side or outer surface of the car roof.

As usual, the roof of the car contains a ventilating space or opening V suitably framed (see 5 parts V') between the inner and outer walls 3 and 3' of the car structure. The opening V contains the adjustable door or swinging panel 4, by which the inflow and outflow of air may be controlled. The base plate 6 of this novel fixture is 10 fastened by bolts or rivets 7, and serves to close the outer side of the space V, becoming a constituent part of the outer wall 3'. The funnel here takes the form of a pipe elbow, the free end of which constitutes the mouth 14' of the funnel, 15 while the base portion 14c, through an opening 6b, communicates with the space V and the interior of the car. The conditioner proper 8, is of larger diameter than the funnel 14 and part-way telescopes over the free end thereof. The conditioner 20 functions to set the air into rapid rotation directly in advance of the mouth of the funnel, and also functions to separate the foreign substances and discharge them from that end of the conditioner which encloses the mouth portion of 25 the funnel. That end of the element contains a circumferential dust-eject opening 16, and, a larger peripheral eject opening 8c, again mentioned herein.

The body of the element 8 is substantially, or 30 in effect, cylindrical, and is of a length substantially equalling its diameter. As best indicated in Fig. 7, it is preferably composed of two halves having lapping edges 8x, and the halves are spot-welded or otherwise united along the longitudinal 35 joints thus provided. The outer or forward end of the element 8 is formed by a whirl-producing tuyère of the radial blade type, characterized by a central disc portion 10 which is of smaller diameter than the hollow body 8. All the blades 8a 40 are inclined or pitched in the same direction, and they circumferentially surround the disc 10. The inwardly pitched or tangential tuyère openings 8a' thus presented, all lead to the interior of the body 8. Assuming a flow of air through this 45 tuyère, it is apparent that the air will take on a whirling motion within the body 8 and thereby the centrifugal separation of heavier particles is accomplished. The latter whirlingly advance upon the inner periphery of the body 8 until 50 arrival at the eject openings 8c and 16; departing from the fixture through those openings along with a considerable proportion of the whirling air. Meantime, a clarified central portion of the 55 whirling air stream departs through the funnel 14 and thus reaches the car. The whirling operation of the air within the body is controlled and rendered uniform by the presence of an internal conical member or bell 9, the wide end 9' of which is coaxial with the mouth of the funnel 60 and preferably of greater diameter. Other functions of this bell will be defined.

All of the fixtures used upon the car are of the same construction but by preference the fixtures are made in pairs, to accommodate the reverse 65 positioning thereof shown in Figs. 1 and 2. This making of "rights" and "lefts" is brought about by the need of the large eject opening in the bottom of each fixture; also by the preferred use of small openings 19 and 20 at the bottom of each 70 funnel or elbow 14 for a purpose to be explained; and, by the desirability of throwing the ejected dust away from the side 3' of the car, to avoid the wear of the dust stream thereon. To accomplish this last the blades 8a are pitched oppositely 75 in the two fixtures of the pair; so that in each case

the whirl of the air at the bottom of the member 8 is downward and outward, away from the side of the car.

A fixture which presents its tuyère or whirl-prompting end to the wind, that is, in the direction of the movement of the car, first receives the air stream and then clarifies and effects pressure upon, and finally discharges clarified air into the car, provided the control damper 4 of the latter is open. The companion fixture, 80 because of its reverse position upon the moving car, effects suction thereon and thus draws the foul air therefrom; again provided that the respective damper be open. By such use of opposed fixtures, the air within the car may be rapidly exchanged for fresh air which is under appreciable pressure and is free from dust. Perhaps the complete elimination of wind-borne dust is too much to claim or expect but at least such seems to be the case; for the dust and moisture excluding 85 performance of the fixture is very perfect.

It will sometimes be thought sufficient to place all fixtures along one side of the car with their funnels pointing in the same direction; and, the identical fixtures being placed upon the other 90 side of the car, will be reversed in direction; so that one side of the car may receive all the fresh air, while the foul air is drawn from the other side of the car.

Referring again to the detailed drawings, it will 105 be noted that the generally circular rather than square member 8 is by preference polygonal in cross-section so that it presents successive longitudinal flats or flat faces 8f, each perpendicular to a plane including the axis of the hollow body. 110 The first benefit thereby secured lies in the better retention of the whirling dust upon the inner periphery of the body 8, the centrifugal separating action upon the whirling dust and water particles being definitely repeated as many times 115 as there are flats. Next, the flat formation permits the body 8 to be firmly welded or otherwise fastened to and against the flat face of the plate 6, in which position it is additionally braced by the two parallel ribs 6c which are formed in or upon 120 the plate 6 and which snugly fit respective adjoining flats 8f of the body 8. Most importantly, the formation of the body 8 from a succession of flats 8f permits the ends of those flats to be shaped as truncated triangles and then to be bent inward, 125 as required to form the curved and inclined blades 8a at one end of the body; and similarly, permits the integral formation of the blades or portions 8b at the other end of the body. Thus 130 integral portions of the original sheet composing the body portion 8 are contrived to form the closed ends of the body.

As best shown in Figs. 3, 4 and 8, the portions 8a are not only bent inward but are pitched as before described as required to form the capacious inlet tuyères or inwardly slanting openings 8a' which constitute the tuyère proper. The inner ends of the triangular parts 8a, being truncated, do not reach to the axis of the body 8; and a central opening remains between the approaching ends. These inner ends, each inclined with respect to the axis, are clamped and held between the two sections of the central disc or rosette 10. As well shown in Figs. 3, 5 and 10, the two parts marked 10 and 11 are provided 145 with interlocking teeth or prongs 10a and 11a which fit opposite sides of the blade ends and those parts are clamped thereon by a riveted spacer 12 which passes through them. The rivet being set, the structure, though composed of rel- 150

atively thin sheet metal parts, takes on an enduring rigidity fully adequate to resist the wind and storm stresses to which it is subjected in its exposed position upon the car.

5 The before mentioned member 9 is preferably of the bell-like shape, well shown in Figs. 3 and 5, and is secured to the inner disc 11 by the same rivet 12 which binds the two-part rosette 10 upon the blades 8a. That member 9, with its flaring 10 inner end, serves as a vortex-defeating cone or element that prevents the exit of dust along the axis of the fixture. In the main, the whirling action induced by the presence of the described tuyère or angularly ported end of the fixture, has 15 the effect of throwing all of the heavier matters outward and against the inner periphery of the body 8, but there is a tendency for straying and lighter substances to approach the axis of the whirl. Such substances are caught in the void 20 formed by the rushing of the whirling air past the flaring end of the member 9 and being first collected upon the inner surface of said member 9, such stray substances form masses of sufficient weight to be expelled centrifugally, and thus 25 are gathered against the distant wall of the body, for sure expulsion at the discharge end of the fixture.

The portions 8b, which resemble the parts 8a, are gently bent inwardly, as well shown in Figs. 3, 30 4, and 5, and their inner ends are slightly lapped one upon the other, in the direction of air rotation within the body 8. The lapped ends are preferably spot welded to give the structure permanence. Thus, a closed end of good appearance 35 is formed upon the fixture and the body 8 is provided with an inner end surface or surfaces which curve gently inward and then extend toward the funnel.

Within that curved end and at its bottom is 40 the discharge port or eject opening 8c, before mentioned, and of a size which permits the free discharge of even large cinders, which may enter the body of the fixture. The inner ends 8d of the blade-like parts 8b form the margin of the opening 16 before mentioned and which is the finer dust eject opening, surrounding the funnel. The capacity of the tuyères 8a' is such as to exceed the capacity of the funnel mouth 14', affording an excess of air to be expelled through 45 the openings 8c and 16. Considerable pressure is built up within the body 8 and hence a blast or waste of air is maintained through the circumferential slot or opening 16 as well as through the larger opening 8c. It follows that any finer dust which does not at once escape from the inner wall and through the opening 8c is successfully ejected through some part of the circumferential 50 eject opening 16.

Virtually only that portion of the air which has 60 been thus freed from dust and moisture is presented or moved inward toward the axis of the fixture and passing through the relatively wide space, a, between the funnel mouth and the central member 9, the clarified air enters the mouth of the funnel in a whirling condition. Being deflected by the end wall 14b of the elbow-like funnel the clear air is turned toward the opening 6b, which forms the terminus of the elbow.

The base of the elbow preferably is rectangular, 70 while the opening 6b is by preference round and of less diameter. A narrow ledge 6b' is thus presented and at the bottom of the funnel adjacent to the ledge 6b' I provide the before mentioned small eject slots 19 and 20. Any residues of dust or moisture which may penetrate the funnel are

ejected from the funnel through these openings 19 and 20, due to the higher pressure of the air within the funnel than upon its exterior. This detail is of special utility at times when the damper 4 is closed. At such times and the wind pressure continuing upon the tuyère end of the fixture, air will whirl through the fixture to the extent permitted by the capacity of the eject openings 8c and 16. During such periods fine dust might accumulate in the elbow, and it is well to provide said openings 19 and 20 in order that such dust may be blown out in advance of the baffle or ring 6b'. That action is ensured by the pressure of the air then occupying the fixture.

In order that the other function of the plate 6 and the relation of the funnel thereto may be clearly understood, special attention is directed to the beforementioned parallel ribs 6c—6c belonging to the plate. These ribs are nearly as long as the plate and so serve to strengthen the same that the plate may be made from a thin sheet of metal, saving weight. As best shown in Figs. 2a, 3, 4, and 6, the ribs are struck up from the plate and their ends are joined by the rectangular 100 struck-up flat 6d, which latter is margined by the inclined cross parts or faces 5 and 5'. The flat 6d contains the hole 6b and forms the beforementioned part 6b'. The space 6a between the ribs forms the seat whereon the member 8 is welded or riveted as before explained. Special attention is directed to the inclined rib surfaces 2—2, 5, and 5' because they are the anchor surfaces for the base of the funnel, as about to be described.

By preference the elbow-like funnel 14 is of 110 the sheet metal construction detailed in the drawings, and as here shaped is easy of manufacture and of good appearance, and is best adapted for stout attachment to the base plate 6. The body of the funnel comprises a single shaped part 14a bent to U-form, except in its forward part where the sides are curved inward to complete the mouth portion 14'. By preference the shape of the portion 14a is made to resemble the polygonal form of the member 8, and this polygonal form persists in the mouth portion 14'. That formation offers flat surfaces which are a convenience in attaching the end plates 14b and 14c. Those plates are shaped to close the ends of the U-shaped section 14a and are provided with inwardly turned tabs 14b' and 14c' which fit the corresponding flat parts of the section 14a. They are spot-welded or riveted thereto, affording desired rigidity. Thus formed and shaped, the elbow harmonizes with the body or conditioner 120 portion 8 and being square at its base it is easy of attachment to the panel or plate 6. To that end the extended edges 17 and 18 of the parts 14a, 14b and 14c are bent outwardly to match the corresponding inclined faces 2, 5 and 5' of the 125 plate 6. Being positioned thereon, they are welded or riveted thereto and thus the raised portion 6d of the plate 6 becomes the base of the funnel.

Reverting to the dust discharge openings or 130 slots 19 and 20 at the bottom of the funnel, it is to be remarked that those openings are sheltered by the bent out portions 15 and 15' of the plates 14b and 14c. In other words, they are open for the discharge of dust, but are closed against 145 the entrance of rain or snow.

When moving forward, the tuyère end of the fixture presents a considerable end surface to the wind and due to the velocity pressure thereof upon the inclined surfaces of the tuyère blades 150

8a, the air enters the hollow body 8 at velocities which ensure its rapid rotation therein. Only a part of the air reaches the car through the funnel, but the supply thus afforded should prove sufficient. If an increased supply of air is needed, the same may be secured by means of an extension collar upon the intake end of the fixture, such as that which is marked 21, appearing in sections upon the end of the fixture shown in Fig. 4. Such an extension is effective in proportion to its cross section, and prevents the oncoming air from glancing off the end of the fixture.

It is to be noted that when the movement of the fixture is reversed in direction, the end surfaces 14b and 8b are presented to the wind and a void is formed at the tuyère end of the fixture. Thereby the desired suction is created upon the funnel. The areas of the openings 8c and 16 are restricted and the direct entrance of air therethrough does not materially diminish the suction upon the funnel.

It is to be distinctly understood that this invention has capabilities of adaptation to and of use upon other vehicles and is not limited to rail-way cars; nor to this preferred location upon the roofs thereof.

Having thus described my invention, what I claim and desire to secure by Letters Patent, is:—
1. The herein described article of manufacture, comprising in a single fixture an air intake funnel adapted for attachment to a passenger car in combination with a dust and cinder separator of the fixed non-rotative type having a whirl-promoting air entrance tuyère and forming the avenue of air entrance to said funnel, the end portion of said separator approaching the sides of said funnel but being circumferentially separated therefrom and therewith providing an annular opening for the discharge of air and fine dust im-

mediately adjacent the mouth of said funnel and said end and the bottom side of the separator together containing a further opening which permits a primary centrifugal discharge of heavier particles at a point radially distant from said funnel, said separator being much greater than said funnel in air reception capacity, thus providing an excess of air and whirling energy when the fixture is in traveling motion and said end and side openings wasting much air and consequently ensuring the discharge of separated cinders and dusts, allowing the discharge of only cleaned air through said funnel.

2. A fixture as claimed in claim 1 and characterized by the polygonal shape of the separator.

3. A fixture as claimed in claim 1 and characterized by tuyère blades which are formed by the flat bent extended ends of a polygonal separator body portion.

4. A fixture as claimed in claim 1 and characterized by a funnel portion of polygonal cross-section.

5. A fixture as claimed in claim 1 and characterized by a separator body of polygonal cross-section and having its ends formed by bent portions of its extended sides, the bent portions at one end being openly inclined to serve as tuyère blades, a hub device serving to lock the inner ends of such blades, and the extended ends at the other end of said body being lapped one upon the other and together forming a central outlet.

6. A fixture as claimed in claim 1 and characterized by a funnel portion of elbow-like form having a flat end and sides for attachment to a support and provided with bent out parts which with said support form residual-dust eject openings.
